AIR OPERATED MEAT CUTTING SAW OR THE LIKE

Ezekiel C. Steiner, 1438 E. Slauson Ave.,
Los Angeles, Calif.

Filed Mar. 20, 1961, Ser. No. 64,386

Term of patent 7 years

(Cl. D93—3)

FIG. 1.

FIG. 2.

FIG. 3.

FIG. 4.

FIGURE 1 is a top plan view of an air operated meat-cutting saw or the like embodying my new design;

FIGURE 2 is a perspective view thereof taken from the lower right of FIGURE 1;

FIGURE 3 is a perspective view thereof taken diametrically opposite that of FIGURE 2; and

FIG. 4 is a perspective view thereof taken from the right of FIG. 3.

I claim:

The ornamental design for an air operated meat cutting saw or the like substantially as shown.
